UNITED STATES PATENT OFFICE.

THEODORE L. VALERIUS, OF FORT ATKINSON, WISCONSIN, ASSIGNOR TO THE CREAMERY PACKAGE MANUFACTURING COMPANY, OF CHICAGO, ILLINOIS, A CORPORATION OF ILLINOIS.

PASTEURIZER AND RIPENER.

1,232,128.

Specification of Letters Patent.

Patented July 3, 1917.

Application filed April 12, 1915. Serial No. 20,370.

To all whom it may concern:

Be it known that I, THEODORE L. VALERIUS, a citizen of the United States, residing at Fort Atkinson, in the county of Jefferson 5 and State of Wisconsin, have invented certain new and useful Improvements in Pasteurizers and Ripeners, of which the following is a specification.

This invention relates to apparatus for 10 ripening cream and for pasteurizing milk and cream.

The object of the invention is to improve the construction of apparatus of this class with a view to increased efficiency and sim- 15 plicity.

In the accompanying drawings, Figure 1 is a longitudinal vertical central sectional view through an apparatus embodying the features of my invention. Fig. 2 is a sec- 20 tional view of an air intake valve. Figs. 3 and 3^a are sectional views of members used in an alternative construction. Fig. 4 is an end elevation of the apparatus, looking from the left-hand end of Fig. 1. Fig. 5 is a frag- 25 mental view. Fig. 6 is a plan view of the parts shown in Fig. 4. Fig. 7 is a sectional view illustrating the manner of attaching a pipe coil to the central shaft. Figs. 8 and 9 are fragmental sectional views illustrating 30 the connections between the central shaft and the feeder tubes.

The embodiment herein shown of my invention comprises a vat 1 which may be of any suitable construction. To the end 1^a 35 of the vat is secured a support 2 having a wall 3 that lies against the end wall 1^a. Upon the wall 3 is a sleeve 4 extending through an opening in the end wall 1^a. The inner end of said sleeve is internally screw- 40 threaded to receive an externally screw-threaded flange 5. To the wall 3 of the support 2 is fixed a gland 6 (Figs. 1 and 5) which projects within the sleeve 4 and serves to retain the packing material 7. The flange 45 5 and the gland 6 constitute a bearing for a tubular shaft or bearing nipple 8. The other end of said shaft is rotatably supported in a bearing member 9 which is secured to a bracket 10 upon the support 2. 50 Fixed upon the shaft 8 is a thrust collar 11 which bears against the portion 12 of the support 2.

At the opposite end of the vat 1 is a circulation tank or ice box 13. In the end wall

1^b of the vat and the opposite wall of the ice 55 box are bearings 14 and 15 to support a tubular shaft or bearing nipple 16.

The shafts 8 and 16 provide means for supporting and rotating a tempering element. Herein the tempering element is 60 shown as comprising a central tube 17 and a spiral pipe coil 18. The central tube and the spiral pipe coil are connected at each end to the shafts 8 and 16 by means of members 19 (Figs. 1 and 7). As said members are 65 identical in construction, a description of one will suffice. Referring to the member which is connected to the shaft 8: said member comprises an internally screw-threaded sleeve 20 arranged to be screwed upon the 70 inner end of the shaft 8. Alined with the sleeve 20 is a sleeve 21 in which the adjacent end of the central tube 17 is secured. Between the sleeves 20 and 21 is a spiral tube 22 which communicates with said sleeves. 75 To the end of said spiral tube is secured the adjacent end of the pipe coil 18. It will be seen that the central tube 17 and the members 19 constitute a shaft having hollow ends which are connected to the bearing nipples 80 or tubular shafts 8 and 16 and to the coil 18.

At suitable intervals the pipe coil 18 is connected to the central tube 17 by means of feeder tubes 23. At their outer ends the tubes 23 are connected to and communicate 85 with the interior of the pipe coil; and at their inner ends the tubes 23 are screwed into sockets 24 formed integral with rings 25, which rings are located within the central tube 17. The sockets 24 communicate 90 with the interior of the tube 17 through holes 26. It will be seen that the tubes 23 serve to convey liquid from the central tube 17 to the pipe coil at various points in the length of the coil, and also serve to support the coil. 95

The ring 25^a (Fig. 8) which is nearest the outlet end of the coil has a web 25^b and constitutes a plug to prevent the tempering fluid from flowing any farther through the tube 17. An opening 26^a establishes communication 100 between the central tube 17 and the feeder tube 23.

The means for rotating the shafts 8 and 16, the central tube 17 and the pipe coil 18 comprises a shaft 27 supported in two bearings 28 which are carried by the wall 3 of the support 2. The shaft 27 is supported at one end by a bearing 29 which is mounted 105

upon the end wall 1^a of the vat. The shaft 27 carries a tight pulley 30 and a loose pulley 31. A spiral pinion 32 on the shaft 27 meshes with a spiral gear wheel 33 on the shaft 8.

Means is provided to permit a circulation of hot or cold water through the rotary tempering element. Said means comprises an outlet fitting 34 which communicates with the tubular shaft 16. To said fitting is secured a pipe 35 which communicates with a spray pipe 36 located within the upper portion of the ice-box 13. 37 is a drain cock connected to the fitting 34. 38 is an overflow tube located within the ice-box, the lower end of said tube communicating with any suitable receptacle (not shown). The height of said tube determines the maximum level of the liquid in the ice-box. 39 is a strainer located within the ice-box and connected by means of a pipe nipple 40 and a T 41 to one end of a pipe 42 which extends longitudinally of the vat. The other end of the pipe 42 is connected by means of a pipe 43 to the interior of the bearing member 9. 44 is a water inlet pipe also communicating with the interior of the member 9. A steam supply pipe 45 having a shut-off valve 46 therein communicates with a nozzle 47 formed integral with the member 9, said nozzle being axially alined with the tubular shaft 8. The rotation of the pipe coil causes a circulation of water through the shaft 8, the central tube 17, the pipe coil 18, the shaft 16, the spray pipe 36 and the pipes 40, 42 and 43, back to the member 9. The heat of the water is imparted to the pipe coil 18 and thence to the milk or cream to be tempered.

40 When the contents of the vat are to be cooled, the hot water is drained off, and cold water admitted to the circulating system through the pipe 44. When the milk or cream has been cooled in this way as much as possible, ice may, if desired, be placed in the box 13, the water supply pipe 44 shut off, and the water caused to circulate by the rotation of the coil 18.

48 (Figs. 1 and 2) is an air-intake valve 50 communicating with the interior of the member 9, for admitting air to prevent the formation of a vacuum. Said valve comprises a body 49 having a plurality of interior guide ribs 50. These ribs serve to guide a valve member 51 which is in the form of an inverted cup. The member 51 normally rests upon shoulders 52. The upper end of the body 49 is closed by a head 53, the lower face of which constitutes a seat for the valve member 51. 54 is a central port in the head 53, said port communicating with the atmosphere through ports 55. Air flows through the ports 54 and 55 and around the valve member 51 and thence through the tube 56 to the member 9. Any

steam or liquid rising in the tube 56 and the body 49 will lift the valve member into contact with the seat 53.

In place of the pipe coil 18, a sheet-metal spiral disk coil similar to the one disclosed in Patent No. 790,466 may be used. The opposite ends of such a spiral disk coil are connected to the tubular shafts 8 and 16 by means of members 57 and 57a (Figs. 3 and 3^a). Each of said members comprises an internally-screw-threaded portion 58 to receive the end of the tubular shaft; the coil with its central tube is supported upon and attached to the opposite ends of said members. Tempering fluid is admitted to the coil through openings 59 and to the central tube through the opening 60. The fluid leaves the coil through the openings 61. The closed end of the member 57a corresponds in function to the web 25^b.

I claim as my invention:

1. A pasteurizer or ripener having, in combination, a vat, a central tube, two alined tubular shafts journaled in the end walls of the vat for supporting and rotating the central tube, a spiral pipe coil communicating at each end with the central tube, rings located in spaced relation along the length of and within the central tube, each of said rings having a socket which communicates with the interior of the central tube, feeder tubes, each having one end seated in one of said sockets and the other end connected to the pipe coil for supporting the coil and establishing communication between the coil and the central tube, a plug in the central tube near one end thereof, a circulation tank arranged to receive liquid from one of the tubular shafts, a pipe connecting the lower portion of the circulation tank with the other one of the tubular shafts, and means for rotating one of said tubular shafts.

2. A pasteurizer or ripener, having, in combination, a coil, a central tube, a tubular shaft alined with the tube, and an integral member for connecting the shaft, the tube, and the coil together, said member comprising a sleeve connected to the shaft, an alined sleeve connected to the central tube; and a spiral tubular portion between said sleeves and connected to one end of the coil, said sleeves and tubular portion communicating with each other.

3. A pasteurizer or ripener, having, in combination, a vat having an end wall, a support having a wall lying in contact with the end wall of the vat, a sleeve on the wall of the support, said sleeve extending through an opening in the end wall of the vat, a flange screwed into the inner end of said sleeve, a gland extending into the other end of said sleeve, a tubular shaft rotatably supported by said flange and gland, and a bearing on said support for said shaft.

4. A pasteurizer or ripener, having, in

- combination a vat, a rotatory hollow tempering element in said vat, two tubular shafts for supporting and rotating said element, a chambered member communicating with one of said shafts, means for supplying tempering fluid to said chambered member, a receptacle arranged to receive fluid from the other tubular shaft, means establishing communication between said receptacle and the chambered member, a tube extending upwardly from said chambered member, and an air intake valve connected to the upper portion of said tube.
5. A pasteurizer or ripener, having, in combination a central tube, a spiral pipe coil communicating at one end with said tube, a member fitting within said tube, said member having a socket which communicates with the interior of said tube, and a feeder tube having one end seated in said socket and the other end connected to the pipe coil.
6. A pasteurizer or ripener having, in combination, a vat, a shaft having hollow ends, hollow bearing nipples connected to said shaft and journaled in the ends of said vat, a hollow coil connected at each end to the interiors of the hollow ends of said shaft, an ice box, the lower portion of said box having an outlet, a pipe connecting said outlet to one of said bearing nipples, a pipe con-
- nected to the other of said bearing nipples and arranged to deliver liquid to the upper portion of said tank and discharge the liquid upon ice placed in said ice box, and means 35 for rotating said shaft whereby liquid is caused to circulate through the ice box and the coil.
7. A pasteurizer or ripener having, in combination, a vat, a shaft having hollow 40 ends, hollow bearing nipples connected to said shaft and journaled in the ends of said vat, a hollow coil connected at each end to the interiors of the hollow ends of said shaft, a circulation tank, stationary means disposed within said tank adjacent the bottom thereof and adapted to be immersed in the liquid contained therein to draw said liquid from the bottom of said tank, a pipe connecting said means to one of said bearing 45 nipples, a pipe connected to the other of said bearing nipples and arranged to deliver liquid to the upper portion of said tank, and means for rotating said shaft whereby liquid is caused to circulate through the tank and 50 the coil.

In testimony whereof, I hereunto set my hand in the presence of two witnesses.

THEODORE L. VALERIUS.
